DESIGN FOR A SUPPORTING BRACKET OR SIMILAR ARTICLE

Thomas C. Keefe, West Roxbury, Mass., assignor
to J. P. Eustis Manufacturing Company, Cam-
bridge, Mass., a corporation of Massachusetts

Application March 17, 1934, Serial No. 51,083

Term of patent 7 years

To all whom it may concern:

Be it known that I, THOMAS C. KEEFE, a citizen of the United States of America, residing at West Roxbury, in the county of Suffolk and Commonwealth of Massachusetts, have invented a new, original, and ornamental Design for a Supporting Bracket or Similar Article, of which the following is a specification, reference being had to the accompanying drawing forming a part thereof.

Fig. 1 is a top view of a bracket showing my new design; and

Figs. 2 and 3 are respectively a side and a front view thereof.

I claim:

The ornamental design for a supporting bracket or similar article substantially as shown.

Signed by me at Cambridge, in the county of Middlesex and Commonwealth of Massachusetts, this 15th day of March, 1934.

THOMAS C. KEEFE.
